UNITED STATES PATENT OFFICE

GEORGE H. STEPHENS, OF NORTHBROOK, ILLINOIS, ASSIGNOR TO THE HAMMOND CLOCK COMPANY, OF CHICAGO, ILLINOIS, A CORPORATION OF DELAWARE

DESIGN FOR A CLOCK CASE

Application filed March 5, 1932. Serial No. 43,096. Term of patent 14 years.

To all whom it may concern:

Be it known that I, GEORGE H. STEPHENS, a citizen of the United States, residing at Northbrook, in the county of Cook and State of Illinois, have invented a new, original, and ornamental Design for a Clock Case, of which the following is a specification, reference being had to the accompanying drawing, forming a part thereof.

The figure is a front perspective view of a clock case showing my new design.

I claim:

The ornamental design for a clock case, as shown.

In witness whereof, I hereunto subscribe my name this 2nd day of March, 1932.

GEORGE H. STEPHENS.
